UNITED STATES PATENT OFFICE.

JOHN DODD, OF OLDHAM, ENGLAND.

MEANS FOR SECURING CARD-CLOTHING TO CYLINDERS OF CARDING-ENGINES.

SPECIFICATION forming part of Letters Patent No. 633,358, dated September 19, 1899.

Application filed January 31, 1899. Serial No. 703,997. (No model.)

To all whom it may concern:

Be it known that I, JOHN DODD, engineer, a subject of the Queen of the United Kingdom of Great Britain and Ireland, and a resident of The Hollies, Werneth, Oldham, in the county of Lancaster, England, have invented certain new and useful Improvements in Means for Securing Card-Clothing to Cylinders of Carding-Engines for Carding Cotton, Wool, and other Fibrous Materials, of which the following is a specification.

This invention consists in improvements in means for securing card-clothing to cylinders of carding-engines, and has for its object the provision of means by which the plugs to which the card-clothing of cylinders of carding-engines is to be attached in order to be secured upon such cylinders may be enabled to resist disturbance and be secured against inward and outward displacement and by which it is made possible to turn the inner surfaces of such cylinders true and smooth without endangering the security of the said plugs.

In the accompanying drawings, Figure 1 is a longitudinal section of so much of the cylinder of a carding-engine as is requisite for the illustration of this invention. Fig. 2 is a longitudinal section of one of the wooden plugs employed according to this invention before insertion in the cylinder of a carding-engine, and Fig. 3 is a side elevation of one of the square wooden pegs or wedges used in securing in position the plugs which are employed according to this invention.

In Fig. 1, *a* is the cylinder to which the card-clothing *b* is to be secured. *c* is the leather or cloth or other foundation in which the wires *d*, forming the card-surface of the card-clothing *b*, are secured, and *e* is one of the fixed bends adjacent to the cylinder *a*.

According to this invention I cause such of the taper plug-holes *f* in the carding-engine cylinder *a* as are to have this invention ap-

plied to them to be tapered or countersunk for a certain distance from the inner surface *g* of the cylinder *a* so that such holes *f* shall be tapered from both the outer and inner faces of the cylinder *a*. The plugs *h* when driven into the said holes *f* are secured by the usual pegs or wedges *j*, driven into the plugs *h*. The inner taper *k* allows the plugs *h* to be expanded by the driving in of the pegs or wedges *j*, so as to form double cones when the pegs or wedges *j* have been driven into them, and enables the plugs *h* to resist disturbance and be secured against both inward and outward displacement, and thus, which is the object of this invention, permits of the inner surface *g* of the cylinder *a* being turned true and smooth without endangering the security of the plugs *h* and permits of the nails or tacks being driven into the plugs to secure the foundation of the clothing to the cylinder *a* without disturbing such plugs.

This invention is applicable to all the cylinders and doffers of carding-engines which require to be covered with wire-clothing.

What I claim, and desire to secure by Letters Patent, is—

The combination of a carding-engine cylinder with holes countersunk or made to taper from both the outer surface and the inner surface of the cylinder, plugs driven into such holes and pegs or wedges driven into such plugs to fasten them and expand them into the form of double cones substantially as set forth.

In testimony that I claim the foregoing as my invention I have signed my name, in presence of two witnesses, this 18th day of January, 1899.

JOHN DODD.
